UNITED STATES PATENT OFFICE.

CHARLES H. CLARK, OF CRAFTON, PENNSYLVANIA, ASSIGNOR TO CLARK CAR COMPANY, OF PITTSBURGH, PENNSYLVANIA, A CORPORATION OF NEW JERSEY.

DUMP-CAR DOORS.

1,136,317.

Specification of Letters Patent. Patented Apr. 26, 1915.

Application filed April 3, 1911. Serial No. 618,523.

To all whom it may concern:

Be it known that I, CHARLES H. CLARK, a resident of Crafton, in the county of Allegheny and State of Pennsylvania, have invented certain new and useful Improvements in Dump-Car Doors, of which the following is a specification.

The object of this invention is to provide a dump car door mechanism of improved construction wherein when the door is closed its load-supporting surface is at a lesser angle than the angle of friction of the lading, provision being had for increasing the angle of the door as it moves from closed position so that all of the lading is discharged. The angle of the door when in open position must at least equal the angle of friction, and in the present invention this is accomplished within limits that simplify and render easy the closing operation. It is also necessary that the door shall operate without interfering with either the trucks or the track, and also without so elevating the hopper, or contracting its load space, as to curtail its capacity.

To secure high efficiency in a dump car door of bodily movable type, the door should be rotatable as well as movable bodily, and the direction of bodily movement should at all times bear such relation to the rotation of the door that the angle of bodily motion, combined with the angle of the door produced by its rotation, is greater than the angle corresponding to the coefficient of friction of the load on the door, without, however, such greater angle being excessive over the friction angle at any position of the door, as such excess requires a corresponding increase of work to close the door.

The foregoing conditions are met by the door of this invention which is so mounted as to move bodily and also to rotate about a single axis instead of a plurality of axes as, for example, in my patent of November 9, 1909, No. 939,588. The door and its hangers constitute a pendulum which swings about its axis or center of oscillation, while the door proper rotates about the center of gyration of the pendulum.

The present adaptation is further characterized by an arrangement of door supports which cause the door to start from closed position in a downwardly curved

path, this initial movement being followed by a rectilinear movement of the door axis at the same time that the door is turning about such axis and increasing its inclination for discharging the lading.

While many of the important features of the invention are embodied in one or a single door, a further feature is the provision of a pair of opposed coöperating doors, each possessing the characteristics to which reference has been made, with the doors preferably so arranged as to have unitary bodily movement; also to provide such doors with locking devices mounted thereon and which coöperate in such way that the doors may be either locked or released from either side of the car.

In the accompanying drawings, Figure 1 is an elevation of the door mounting, the car frame being shown in section on line 1—1 of Fig. 3. Fig. 2 is a view in top plan of one of the door-supporting mechanisms and portions of the doors. Fig. 3 is a side elevation of a portion of a car equipped with the improved door mechanism, part thereof being broken away. Fig. 4 is a sectional detail on line 4—4 of Fig. 1.

Referring to the drawings, 2 designates the sloping side sheets, and 3 the end sheets of the hopper, the latter provided with the depending aprons 4 around which the door ends close, 5 are the doors, and 6 their upturned ends. 7 is a beam on the under side of each door with its projecting ends 8 each provided with a bracket 9 which forms a bearing for the trunnion pin 10. The axes of trunnions 10 are horizontal, and the trunnions at opposite ends of each door are in axial line with each other and define the axis about which the door rotates. Each door is wholly supported about this axis, and the supporting means is so sustained as to be movable relatively to the door-closed space, thus affording the door its bodily movement as distinguished from its rotary or axial movement.

In the present adaptation the movable door supports are embodied in links 11, which at their lower ends provide bearings for the trunnion pins 10, and at their upper ends are sustained and swing on pins 12 in direction transversely of the door-closed opening. Pins 12 may be variously sustained. As here shown they comprise the

spindles of rollers 13, with each roller movable in a depressed horizontal track portion 14 of bar 15 which may be supported transversely of the car in any suitable manner, in the present instance being secured to draft sills 16. Each link 11 is in effect a pendulum arm of which supporting pin 12 is the center about which the pendulum oscillates, while trunnions 10 define the center of gyration of the pendulum and about which the door proper rotates.

Two doors are here shown arranged to close together at their lower edges at the center line of the car, and when thus closed each of supporting links 11 extends inward from a vertical line intersecting the pin 12, the inner end of depressed track 14 stopping roller 13 in order to maintain the links in the position described. The inclination of each door when closed may be less than the angle of friction of the door-supported lading, so that when the door opens its inclination is increased for discharging the load. With links 11 deflected from the vertical as above described, the bodily movement of the doors causes their lower edges to move in a downward and outward direction as they start from closed position and until pins 10 align vertically with pins 12, after which the bodily movement of the doors is in the direction defined by tracks 14, in the present embodiment such movement being horizontal; as shown in dotted lines in Fig. 1. Coincidentally with such horizontal movement the inclination of each door may be increased by its rotation on axle pins 10. The extent of such rotation varies. It may not be appreciable, and again it may be as full as possible throughout the opening movement. Whatever the rotation, determined by the conditions attending each dumping operation, the door is unconfined and may or may not rotate while dumping the load as conditions may determine, the only limitation being the provision of means for stopping its rotation when fully open, also means for defining maximum rotation if attained before the door is fully open. The doors may swing upwardly against the side sheets, as in dotted lines in Fig. 1, the latter serving to define the maximum opening rotation at any position of the doors between fully open and closed positions. Shoes 18 on the side sheets are engaged by the doors, and the outturned upper ends 19 of the shoes form stops for their upper edges which, together with stops 20 on track bar 15 for links 11, limit the opening movement. If the upper edges of the doors are not in engagement with shoes 19 when stops 20 are engaged by links 11, the stopping of the latter will cause the doors to rotate until their upper edges engage stops 19.

While the center of gravity of the door 65 may be variously located, the arrangement

is preferably such that its position is inward slightly from the door axis defined by pins 10 when the door is closed, as thereby the described initial movement of the door is assured, and the door is maintained with its outer portion uppermost when fully open.

In order that both doors may be either released for opening, or locked in closed position, by one operation, they are cross-connected so that operation of one door necessarily results in the operation of the other door. This arrangement is especially desirable when the doors are equipped with coöperating latch devices 21, which may be operated interchangeably for releasing and for locking the doors, the latch-carrying shafts 22 being utilized for swinging the doors by hand, all as fully set forth in my Letters Patent of November 9, 1909, No. 939,588.

As here embodied the door-connecting mechanism, located at each end of the pair of doors consists of a shaft or spindle 23 which is centered in track bar 15 and apron 4, Fig. 4, with crank arms 24 of the spindle connected by links 25 with axle pins 10. The desired unitary bodily movement of the doors when opening and when closing is thus secured without interfering with the rotation of the doors about their respective axes. The doors move to open position without injurious shock and are so nearly balanced when closed and sustaining the load, and also when open and free from load, that they may be manipulated by an operator at either side of the car.

I claim:

1. A pair of bodily movable doors for a dump car with each door rotatable about a single axis and with the doors wholly supported in all positions thereof at such axes.

2. A pair of opposed bodily movable doors for a dump car adapted to engage each other when closed, each door being rotatable about a single axis and the doors supported in all positions thereof at such axes, and means for securing the doors together in closed position.

3. A pair of opposed bodily movable doors for a dump car with each door rotatable about a single axis and with the doors wholly supported in all positions thereof at such axes, and means carried by the doors for holding them closed.

4. A pair of opposed bodily movable doors for a dump car with each door rotatable about a single axis and with the doors wholly supported in all positions thereof at such axes, and means mounted on the respective doors and adapted to coöperate in holding the doors in closed position.

5. A pair of opposed bodily movable doors for a dump car, each door rotatable

- about a single axis and with the doors wholly supported in all positions thereof at such axes, the axis of each door being movable laterally from its normal door-sustaining position, and means for securing the doors together in closed position with said axes deflected from normal position.
6. A pair of opposed bodily movable doors for a dump car, supporting means for each door with such supporting means having a center of oscillation and a center of gyration with the door revoluble about such center of gyration and with the doors wholly supported in all positions thereof at the centers of gyration, and means for securing each door to the other door when in closed position.
7. In a door for a dump car, the combination of hangers adapted to oscillate about a horizontal axis, means for shifting the axis of oscillation of the hangers, and a door rotatable about a single axis and supported by the hangers at such axis.
8. A door for a dump car rotatable about a single axis and wholly supported at such axis in every position of the door, said axis being fixed relatively to the door and movable relatively to the door-closed opening.
9. A bodily movable door for a dump car rotatable about a horizontal axis and wholly supported at such axis, in combination with pivoted hangers on which the door is supported at its axis of rotation, and shifting supports for the hangers.
10. A bodily movable door for a dump car rotatable about a single horizontal axis and wholly supported at such axis, in combination with hangers alining with each other longitudinally of the door and connected to the later coincidentally with its axis of rotation, and shifting sustaining means for each hanger.
11. An inclined bodily movable door for a dump car, oscillating hangers sustained at a common axis, the door rotatable on the hangers about a single axis and wholly sustained at such axis, the axis of rotation of the door and the axis of oscillation of the hangers being parallel with each other and with the higher portion of the door, and means for directing the higher portion of the door as the door moves to full open position.
12. An inclined bodily movable door for a dump car, supports mounted to oscillate in the direction of movement of the door and on which the door is mounted to rotate on an axis paralleling the longitudinal edges of the door, means for directing the higher edge of the door, and stop means engaged by said higher edge when the door is fully open.
13. A bodily movable door for a dump car, and supporting means arranged to im-
- part only a revolving movement to the door as it starts from closed position and then to impart thereto simultaneously a combined revolving and rectilinear movement.
14. A bodily movable door for a dump car supported and rotatable about a horizontal axis, and supporting means to which the door is rotatably connected at its axis of rotation with the supporting means arranged to impart only a revolving movement to the door as it starts from open position and to follow such revolving movement with a combined revolving and rectilinear movement.
15. A bodily movable door for a dump car wholly supported and rotatable about a horizontal axis, and movable door supporting means operating to so move the door as to cause said axis of rotation to move in a downwardly curved line as the door starts from closed position and to then move said axis in a right line during the remainder of the opening movement.
16. A bodily movable rotatable door for a dump car having a single axis of rotation, and supports on which the door rotates, the supports adapted to oscillate about a common axis which shifts relatively to the door-closed opening as the door opens and closes.
17. A bodily movable rotatable door for a dump car having a single axis of rotation, tracks, and door supports movable on the tracks with the door rotatable on said supports.
18. A bodily movable rotatable door for a dump car, tracks, links alining with each other at right angles to the tracks and mounted on rollers which travel on the tracks with the door mounted to rotate on said links.
19. A bodily movable rotatable door for a dump car, tracks, rollers movable on the tracks, links mounted to oscillate about the roller axes, said links being connected to and supporting the door and on which the door is rotatably mounted.
20. A bodily movable rotatable door for a dump car, tracks disposed transversely of the door-closed opening, links movably sustained on the tracks, the door rotatable on and supported by the links.
21. A bodily movable door for a dump car having a single axis of rotation, depending supports connected to the door coincidentally with such axis, and sustaining means for the supports located above such axis of rotation of the door and on which the supports are movable bodily during the opening and closing movement of the door.
22. A bodily movable door for a dump car having a single axis of rotation, depending supports connected to the door coincidentally with such axis, sustaining means for the supports located above such axis of ro-

- tation of the door and on which the supports are movable bodily during the opening and closing movement of the door, and means for limiting the rotation of the door.
- 5 23. The combination of an open bottom car body, a pair of bodily movable doors therefor, each door rotatable about a single axis, and depending supports for each door connected thereto at its axis of rotation, the 10 supports sustained above their connections with the door and movable bodily relatively to the door-closed opening.
24. The combination of two bodily movable doors for a dump car each rotatable about a single axis and supported at such 15 axis, depending supports connected to the doors at such axes and on which the doors rotate, and sustaining means for the supports located above the door axes and on 20 which the supports are movable bodily as the doors open and close.
25. The combination of a dump car hopper, opposite bodily movable doors therefor inclined when closed and mounted to increase 5 their inclination when opening with their higher portions movable upwardly at opposite sides of the exterior of the hopper and guided thereby, each door rotatable about a single horizontal axis located intermediate 30 its upper and lower edges, and depending supports mounted to oscillate as the doors open and close, with the doors wholly supported by and mounted to rotate on said supports.
- 35 26. The combination of a pair of bodily movable doors for a dump car each rotatable about a single axis and wholly supported at such axis, supporting means for the doors, and means connected to both doors causing 40 them to move bodily in unison.
27. The combination of a pair of bodily movable doors for a dump car each rotatable about a single axis, and cranks rotatable at
- the center of the car and connected to the respective doors at the door axes. 45
28. The combination of a pair of bodily movable doors for a dump car, supporting means for each door, cranks located at the center of the car at opposite ends of the doors, and connections between the cranks and the doors causing the doors to move bodily in unison.
29. The combination of a pair of bodily movable doors for a dump car, each door rotatable about a single horizontal axis and wholly supported at such axis, bodily movable supports for the doors, and mechanism causing the door supports to move in unison. 55
30. The combination of a pair of bodily movable doors for a dump car, each door rotatable about a single axis, supports for the doors movable transversely of the door-closed opening, and mechanism connected to the doors at their axes of rotation for causing the supports to move in unison. 60
31. The combination of a pair of bodily movable doors for a dump car, each door supported and rotatable about a single axis, supports for the doors movable bodily transversely of the door-closed opening, means for limiting the rotary movement of the doors, and cross connecting mechanism for causing the doors to move in unison. 65
32. The combination of a pair of bodily movable doors for a dump car, each door rotatable about a single axis, supports for the doors movable bodily transversely of the door-closed opening, a shaft located between the doors, and cranks on the shaft connected to the doors. 75
- In testimony whereof I affix my signature in presence of two witnesses.
